UNITED STATES PATENT OFFICE.

RAYMOND D. SMITH, OF ARLINGTON, MASSACHUSETTS, ASSIGNOR TO TREMONT PRODUCTS COMPANY, OF BOSTON, MASSACHUSETTS, A CORPORATION OF MASSACHUSETTS.

THERMOSTATICALLY-CONTROLLED ROTARY SWITCH.

1,334,181.

Specification of Letters Patent. Patented Mar. 16, 1920.

Application filed September 12, 1916, Serial No. 119,757. Renewed June 11, 1919. Serial No. 303,478.

To all whom it may concern:

Be it known that I, RAYMOND D. SMITH, a citizen of the United States, residing at Arlington, in the county of Middlesex and State of Massachusetts, have invented certain new and useful Improvements in Thermostatically-Controlled Rotary Switches, of which the following is a specification.

My invention relates to rotary switches for the control of electric circuits and specifically to that form of rotary switch adapted by progressive stages of rotation to alternately make and break a circuit.

The object of my invention is to provide in such a switch, improved thermostatically controlled detent means which shall act normally to restrain the rotatable contact element in a circuit closing position when manual actuation is effected as normally adapted to open the circuit, and to provide means operated by the usual manual actuating instrumentality, thereby to render active a normally inactive and deenergized device for heating the thermostat, for causing a delayed automatic release of the said contact element from its restraining detent.

Other objects of my invention reside specifically in improved details of construction and arrangement of the thermostatically controlled detent; while novel and advantageous arrangements of parts, affording compactness and durability, will be evident from the following description and from the drawings hereof.

In the drawings, Figure 1 is an enlarged vertical section taken through the switch on the plane 1—1 of Fig. 2; Fig. 2 is a plan view of the switch showing the movable contact clips in their circuit closing position; Fig. 3 is a diagrammatic view showing the operation of my improved detent device and controlling thermostat; Fig. 4 is a view in perspective, showing the actuating shaft and its carried parts; Fig. 5 is a diagram of electrical connections; Fig. 6 is a plan view similar to Fig. 2 showing the lead wires and their respective connections; Fig. 7 is a partial view of certain detent parts and of the cam actuated sliding dog

taken partly in section on the horizontal plane 7—7 in Fig. 1; Fig. 8 is a view taken partly in section on the horizontal plane 8—8 in Fig. 1 showing the auxiliary contacts open; Fig. 9 is a plan view of the contact clips in their circuit opening position; Fig. 10 shows a detail of construction and is taken in section on the plane 7—7 in Fig. 1, the actuating shaft and cam carried thereby being shown advanced 90° and the main contact-carrying structure thereby freed from engagement with the stationary ratchet wheel to permit tension caused follow-up movement of said structure relative to the shaft; Fig. 11 is a sectional view similar to Fig. 8, showing the auxiliary contacts closed.

Throughout the drawings and in the following description, similar parts are designated by like numerals.

In Figs. 1 and 2 the insulating base 10 is shown carrying stationary contact blades 11, 12 and in a lower horizontal plane the blades 13 and 14 (not shown in Fig. 1) these blades being positioned to be engaged in diametrically opposite pairs by the superposed and insulated contact clips 15 and 16 which bridge the switch at right angles. The contact clips together with cam plate 17 carrying the said clips and insulated therefrom, form a structure loosely rotatable on the actuating shaft 18. Shaft 18 is provided with a lower bearing 19 and an upper bearing 20 which bearings are contained in bracket plates 21 and 22 respectively the said bracket plates being fixed to the lower and upper surfaces respectively of the insulating base 10. In Fig. 4 it is clearly shown that the shaft 8 fixedly carries a collar 24, a cam 25 and at its lower extremity an auxiliary contact clip structure composed of the detent plate 26 and the conductive clips 27 insulated therefrom. A spring 28, loosely coiled about the shaft 18, engages with a notch 29, in the collar 24 and with the plate 17 for establishing a tensioned connection between the shaft 18 and the main contact clip structure. The usual sliding dog plate 30, by engagement of its projection

31 with a stationary ratchet wheel 32, opposes the action of spring 28 but is manually releasable from such opposing engagement by the action of cam 25 in the elongated slot 33 of the dog plate 30 (when suitable tension has been established to break the circuit)—this type of switch construction for producing quick break of the circuit, being well known in the art.

10 I have provided on the cam plate 17, two diametrically opposite, extending portions 34, 34 which in turn and in alternate stages of rotation are arranged to be intercepted in their tension caused rotation by a bell-crank detent lever 35 pivoted at 36, as shown in Fig. 2. The detent lever 35 is normally maintained in a position to so engage the portions 34 by means of a small spring 37. It will be evident however that 20 the arrangement of parts is such that strong enough rotative tendency of the detent plate 17 would be operative to effect release from the detent lever 35 against the action of spring 37. Such release however is prevented normally by a projecting plate 38 made fast to the inner surface of a bimetallic thermostat 39 which thermostat at one end is securely anchored to the upper bracket plate 22 and which at the other end 30 is formed inwardly to engage with a roller abutment 41. The roller 41 without frictionally opposing the heat caused movement of the thermostat (which is in this case of a straightening nature or generally out-bending) substantially reinforces the thermostat against the thrust imparted to it by the lever 35. The relative releasing movements of these detent parts are clearly shown in Fig. 3.

40 Carried by the lower bracket plate 21 is a detent spring 40 which engages the detent plate 26 upon actuation of key shaft 18 to open the circuit, and which by such engagement acts co-operatively with the detent lever 35 to establish a tensioned relation between the shaft 18 and the main clip structure in an obvious manner, so that upon thermostatically caused release of the lever 35, the clip structure will be rotatively advanced, automatically to break the circuit by the tension in spring 28.

Such delayed release of the lever 35 is caused by connecting into circuit the resistive, heating winding 42 (which is carried by and insulated from the thermostat) 55 by means of the auxiliary clips 27 which clips move with the shaft 18 to make such circuit between the auxiliary contact blades 43, 43 as shown in Figs. 8 and 11. The thermostat is thereby energized and after a time interval moves as indicated in Fig. 3 to release the detent lever 35. A casing 60 appears at 45 and an indicator dial at 46 carried by the shaft 18 and therefore movable with the controlling button 47 thereby

indicating the "on" position of the switch and the position of the shaft 18 when actuated and held for causing delayed automatic opening of the circuit.

Although I have described my invention 70 herein as comprising a rotary switch embodying my improved arrangement of thermostatically controlled detent mechanism, it will be appreciated that the novel and advantageous features embodied in the details 75 of this mechanism are applicable to the control of any tension-actuated device or member, and it will further be apparent that material departure may be made from the exact structural arrangement herein disclosed, and still avail of the new and useful application of principles shown by the invention. For instance, the detent lever 35 need not necessarily be pivoted to a stationary frame portion but may be carried by the 80 tension-actuated member itself (in this case the cam plate 17), as is illustrated and described in my copending application, Serial No. 165,026, where the tension-actuated member is embodied as the stem of a rotatable gas valve. Certain of the appended claims, accordingly, are not limited to my invention as embodied specifically in an electric switch; but are intended to define the broadly novel means by which a simple 85 flexing thermostat may be rendered efficiently operative for heavy duty.

The mechanical principles involved in the thermostatic detent herein disclosed are such that a relatively heavy circuit opening spring may be employed and be satisfactorily controlled by a necessarily thin and limber thermostat, incapable in itself of producing much power for overcoming frictional resistance to the disengagement of a 105 restraining detent.

Having thus described herein an illustrative embodiment of my present invention, and without limiting the scope thereof to such precise embodiment what I claim is:

1. A thermostatically controlled device comprising, in combination; a rotatable member adapted to be tensioned for unidirectional movement; a bell-crank lever positioned on a pivot operatively at one end to intercept said member and upon movement to release said member; and a bimetallic resilient thermostat, having a projecting detent mounted thereon and positioned normally so that said detent engages said lever at the opposite end and is operative to hold the latter in said intercepting position, the position of said pivot relative to the direction of thrust of said member on said lever, and of said lever of said detent, being such that said thrust tends to displace the thermostat and detent in a direction approximately similar to that of the designed thermally caused movement thereof.

2. A thermostatically controlled device 130

- comprising, in combination; a rotatable member adapted to be tensioned for uni-directional movement; a bell-crank lever positioned on a pivot operatively at one end 5 to intercept said member and upon movement to release said member, with spring means operatively arranged to restore said lever to its intercepting position;—and a bimetallic resilient thermostat, having a projecting detent mounted thereon, and positioned normally so that said detent engages said lever at the opposite end and is operative to hold the latter in said intercepting position,—the position of said pivot relative 10 to the direction of thrust of said member on said lever, and of said lever of said detent, being such that said thrust tends to displace the thermostat and detent in a direction approximately similar to that of 15 the designed thermally caused movement thereof, together with a reinforcing arrangement for said thermostat embodying, with a coöperative conformation of a free part of the thermostat, a stationary anti-frictional support positioned to be engaged thereby when said member engages said lever, the coöperative arrangement and position being such that designed thermally caused movement of said thermostat is operatively unconstrained by said support and such that the lines of pressure of said thermostat on said support and of said lever on 20 said spur detent are substantially parallel.
3. The combination with a tension-actuated member of thermostatically controlled 25 detent mechanism for governing the movement thereof, embodying a movable detent element having a constraining support, arranged normally in operative relation to 30 said member, and adapted to yield for permitting said movement thereof; a movable stop arranged in one position thereof to intercept said element and to resist the said yielding thereof; and an abutment-supported, 35 flexing thermostat, having operative connection to said stop whereby thermally-caused flexure in said thermostat retracts said stop from engagement with said element,—the coöperative formation and 40 positioning of said member, said element with its support, and of said stop, being such that a component only of the thrust imposed by said member upon said element is borne by said stop and is rendered operative to assist thermostatic retraction of the 45 latter.
4. The combination with a tension-actuated member of thermostatically controlled 50 detent mechanism for governing the movement thereof, embodying a pivoted lever normally arranged in operative relation to said member and adapted to yield about its pivot for permitting said movement of the member; a movable stop arranged in one 55 position thereof to intercept said lever and to resist the said yielding thereof; and an abutment-supported, flexing thermostat, having operative connection to said stop whereby thermally-caused flexure in said thermostat retracts said stop from engagement with said lever,—the coöperative formation and positioning of said member, said lever with its pivot, and of said stop, being such that a component only of the thrust imposed by 60 said member upon said lever is borne by said stop, and is rendered operative to assist retraction of the latter by the thermostat.
5. The combination with a tension-actuated member of thermostatically controlled 65 detent mechanism for governing the movement thereof, embodying a pivoted lever normally arranged in operative relation to said member and adapted to yield about its pivot for permitting said movement of the 70 lever with said lever,—the coöperative formation and positioning of said member, said lever with its pivot, and of said stop, being such that a component only of the thrust imposed by said member upon said lever is borne by said stop, and is rendered operative to assist retraction of the latter by the thermostat.
6. The combination with a tension-actuated member of thermostatically controlled 75 detent mechanism for governing the movement thereof, embodying a pivoted lever normally positioned in the path of movement of said member and adapted to yield therefrom about its pivot for permitting said movement 80 of the member; a movable stop arranged in one position thereof to intercept said lever and to resist the said yielding thereof; and an abutment-supported, flexing thermostat, having operative connection to said stop 85 whereby thermally-caused flexure in said thermostat retracts said stop from engagement with said lever,—the coöperative formation and positioning of said member, said lever with its pivot, and of said stop, 90 being such that a component only of the thrust imposed by said member upon said lever is borne by said stop, and is rendered operative to assist retraction of the latter by the thermostat.
7. The combination with a tension-actuated member of thermostatically controlled 95 detent mechanism for governing the movement thereof, embodying a pivoted lever normally positioned by resilient means to 100 intercept said member and adapted to yield about its pivot and retreat from said intercepting position when engaged by said member, thereby to permit said movement of the latter; a movable stop arranged in one position thereof to intercept said lever and to resist the said yielding thereof; and an abutment-supported, flexing thermostat, having operative connection to said stop whereby 105 thermally-caused flexure in said thermostat retracts said stop from engagement with said lever,—the coöperative formation and positioning of said member, said lever with its pivot, and of said stop, being such that a component only of the thrust imposed by 110 said member upon said lever is borne by said stop, and is rendered operative to assist retraction of the latter by the thermostat.
8. The combination with a tension-actuated member of thermostatically controlled 115 detent mechanism for governing the movement thereof, embodying a pivoted lever normally arranged in operative relation to said member and adapted to yield about its pivot for permitting said movement of the member; a movable stop arranged in one position thereof to intercept said lever and to resist the said yielding thereof; and an abutment-supported, flexing thermostat, having operative connection to said stop whereby 120 thermally-caused flexure in said thermostat retracts said stop from engagement with said lever,—the coöperative formation and positioning of said member, said lever with its pivot, and of said stop, being such that a component only of the thrust imposed by 125 said member upon said lever is borne by said stop, and is rendered operative to assist retraction of the latter by the thermostat.

member; a movable stop arranged in one position thereof to intercept said lever and to resist the said yielding thereof; and a bimetallic, flexing thermostat, abutment-supported at one end thereof and at a free portion provided with operative connection to said stop whereby thermally-caused flexure in said thermostat retracts said stop from engagement with said lever,—the co-operative formation and positioning of said member, said lever with its pivot, and of said stop, being such that a component only of the thrust imposed by said member upon said lever is borne by said stop, and is rendered operative to assist retraction of the latter by the thermostat.

8. The combination with a tension-actuated member of thermostatically controlled detent mechanism for governing the movement thereof, embodying a pivoted lever normally arranged in operative relation to said member and adapted to yield about its pivot for permitting said movement of the member; a movable stop arranged in one position thereof to intercept said lever and to resist the said yielding thereof; and a bimetallic, flexing thermostat, abutment-supported at one end thereof and at a free portion provided with operative connection to said stop whereby thermally-caused flexure in said thermostat retracts said stop from engagement with said lever,—the co-operative formation and positioning of said member, said lever with its pivot, and of said stop, being such that a component only of the thrust imposed by said member upon said lever is borne by said stop and thermostat, and thereby assists the latter to retract the former as said.

40 9. The combination with a tension-actuated member of thermostatically controlled detent mechanism for governing the movement thereof, embodying a pivoted lever normally arranged in operative relation to said member and adapted to yield about its pivot for permitting said movement of the member; a movable stop arranged in one position thereof to intercept said lever and to resist the said yielding thereof; and a bimetallic, flexing thermostat, abutment-supported at one end thereof, carrying at a free portion thereof said stop, and adapted by thermally-caused flexure to retract the latter from engagement with said lever,—the co-operative formation and positioning of said member, said lever with its pivot, and of said stop, being such that a component only of the thrust imposed by said member upon said lever is borne by said stop and thermostat, and thereby assists the latter to retract the former as said.

60 10. The combination with a tension-actuated member of thermostatically controlled detent mechanism for governing the movement thereof, embodying a pivoted lever

normally arranged in operative relation to said member and adapted to yield about its pivot for permitting said movement of the member; a movable stop arranged in one position thereof to intercept said lever and to resist the said yielding thereof; and a bimetallic, flexing thermostat, abutment-supported at one end thereof, carrying at a free portion thereof said stop, and adapted by thermally-caused flexure to retract the latter from engagement with said lever, the co-operative formation and positioning of said member, said lever with its pivot, and of said stop, being such that the thrust imposed by said member upon said lever is borne in part by said pivot and in part by said stop and thermostat, and thereby assists the latter to retract the former; together with a constraining abutment for the free end of said thermostat, so formed and positioned relative thereto that the thermostat is reinforced thereby against mechanical flexure due to said thrust, but is unrestrained thereby in thermally-caused movement.

11. In an electric switch including a rotary contact member adapted alternately to make and break a circuit and a spring connected, manually operable device for actuating the same, in combination; an insulated projection extending radially from said contact member, a pivoted detent lever normally positioned in the path of movement of said projection, and adapted to yield therefrom about its pivot for permitting tension-caused circuit controlling movement of said member; a movable stop arranged in one position thereof to intercept said lever and to resist the said yielding thereof; and an abutment-mounted, flexing thermostat, having operative connection to said stop whereby thermal energization of said thermostat retracts said stop from engagement with said lever; together with an electric heating unit for thermally energizing the thermostat.

12. In an electric switch including a rotary contact member adapted alternately to make and break a circuit and a spring connected, manually operable device for actuating the same, in combination; an insulated projection extending radially from said contact member, a pivoted detent lever normally positioned in the path of movement of said projection, and adapted to yield therefrom about its pivot for permitting tension-caused, circuit-controlling movement of said member; a movable stop arranged in one position thereof to intercept said lever and to resist the said yielding thereof; and an abutment-mounted, flexing thermostat, having operative connection to said stop whereby thermal energization of said thermostat retracts said stop from engagement with said lever,—the co-operative formation and positioning of said

projection, said lever with its pivot, and of
said stop, being such that a component only
of the thrust imposed by said projection on
lever is borne by said stop, and is rendered
5 operative to assist retraction of the latter by
the thermostat, and an electric heating unit
for thermally energizing the thermostat.
